DESIGN FOR AN AUTOMOBILE MUDGUARD

Edward J. Meyer, Kansas City, Mo.

Application July 23, 1936, Serial No. 63,997

Term of patent 3½ years

To all whom it may concern:

Be it known, that I, Edward J. Meyer, a citizen of the United States, residing at Kansas City, in the county of Jackson and State of Missouri, have invented a new, original, and ornamental Design for an Automobile Mudguard, of which the following is a specification, reference being had to the accompanying drawing, forming part thereof, in which,

Figure 1 is a perspective view of an automobile

mudguard showing my new design, the salient feature thereof being shown in full lines.

Figure 2 is a fragmentary sectional view of the mudguard shown in Figure 1.

I claim:

The ornamental design for an automobile mudguard, substantially as shown and described.

EDWARD J. MEYER.
